LOCK SWITCH FOR FLASHLIGHTS

Joseph F. Moran, Waterbury, Conn., assignor to
Scovill Manufacturing Company, Waterbury,
Conn., a corporation of Connecticut

Application October 19, 1933, Serial No. 694,349

1 Claim. (Cl. 200—60)

This invention relates to electric flashlights, and more particularly to an improved lock switch for controlling the current flow through a flashlight bulb.

5 One object of this invention is to provide a switch of the above nature having a movable contact which is actuated by a slidable and depressible push-button to permit the lamp bulb to be flashed on momentarily or mechanically held lighted for as long a period as may be desired.

10 A further object is to provide a flashlight switch of the above nature having mechanism for positively locking the sliding push-button in open-circuit position so as to prevent accidental prolonged closing of the switch.

15 A further object is to provide a flashlight of the above nature which will be simple in construction, inexpensive to manufacture, easy to assemble and manipulate, compact, ornamental in appearance, and very efficient and durable in use.

20 With these and other objects in view there have been illustrated on the accompanying drawing two forms in which the invention may be conveniently embodied in practice.

25 In the drawing:

Fig. 1 represents a fragmentary view in elevation and partly in longitudinal section of a flashlight, showing the switch mechanism locked in open-circuit position.

30 Fig. 2 is a face view of a portion of the casing, showing the first form of switch construction.

35 Fig. 3 is a longitudinal sectional view through the same, showing the push-button in momentary depressed position.

40 Fig. 4 is a view similar to Fig. 3 with the switch mechanism latched in "on" or closed-circuit position.

45 Fig. 5 is a longitudinal sectional view of a modified form of switch construction, showing the switch locked in open-circuit or "off" position.

Fig. 6 is a view similar to Fig. 5 with the switch in closed-circuit position.

50 Fig. 7 is a face view of the same.

Referring now to the drawing in which like reference numerals denote corresponding parts throughout the several views, the numeral 10 indicates a flashlight battery casing having an externally threaded closed upper end 11 for receiving a head 12 carrying the usual parabolic reflector 13, and a flat sided lens 14, the latter being seated on an annular shoulder 15 formed on the rim of the reflector 13 and held in place by a detachable lens ring 16 which is screwed upon

the upper part of said head 12. The head 12 also has the usual lower threaded section 17 by means of which it may be adjustably screwed upon the upper section 11 of the casing so as to permit longitudinal adjustment of the reflector 13 with respect to a lamp bulb 18, the latter being screwed into a threaded metal socket 19 mounted upon the adjacent closed end 11 of the casing 10. The lower end of the casing 10 is closed by the usual screw threaded cap 20, which electrically connects the base terminal of a series of dry cells 21 to the casing 10, which in turn is electrically connected at the top with the lamp socket 19.

5 The closed end 11 of the casing 10 is provided with the usual central opening 22 through which the center terminal 23 of the lamp bulb 18 extends into contact with a downwardly offset angular conductor strip 24, having a downturned section 24a located adjacent the side wall of the casing and having a flexible lower end 24b which forms the movable contact of the switch. The end 24b is adapted to be forced inwardly by a push-button-operated spring strip 25 into contact with the lower inwardly offset vertical end 26 of an angular metallic strip 26a forming the stationary 25 contact of the flashlight switch.

10 The horizontal upper section 27 of the angular strip 26a is bent inwardly and offset downwardly at 28 into contact with the upper cell terminal 29. The vertical member 26 is secured to the casing 10 by an insulating eyelet 30 which also forms an anchorage for the lower end of the flexible strip 25. It is also secured to the casing by an intermediate eyelet 30a. The horizontal section 27 of said angular strip is likewise joined by an insulating eyelet 31 to the upper conductor strip 24, and to the closed end of the casing by an insulating eyelet 32. The strips 24a and 26a are insulated from each other by a strip of insulation 33 and the strip 24a is provided on its upper and outer sides with a protective strip of insulation 34. The insulating strip 33 terminates at a point considerably above the lower end of the strip 24b so as to produce a good electrical connection between the contacts of the switch 45 when the push-button is operated. This construction is fully described in a prior Patent No. 1,894,606 to M. H. Bennett, dated January 17, 1933, and it will be clear that when such electrical connection is established, the circuit through the 50 flashlight lamp 18 will be closed.

15 In order to control the electric circuit including the lamp and batteries, provision is made of a depressible and slidable ball push-button 35 located within an aperture 36 formed in a raised 55

section 37 of an escutcheon plate 38 secured to the casing by the insulating eyelets 30 and 30a. The ball 35 is adapted to rest within an inwardly offset seat 39 of the resilient spring strip 25 which 5 rests against the lower end of the insulating strip 34 in alinement with the bottom extremity of the movable contact 24b. The push-button ball 35 is also guided by a sliding thumb piece 40 secured to the escutcheon plate by depending lugs 41 extending through slots 42 in said escutcheon plate. A locking plate 43 is located under the escutcheon plate for cooperating with the spring strip 25, and is connected to the thumb-piece 40 by means 10 of the lugs 41 which pass therethrough, and are bent over to rigidly connect said locking plate 43 to said thumb-piece 40.

The middle sections of the thumb-piece 40 and the locking plate 43 are provided with a pair of aligned apertures 44 and 45 having their edges 20 countersunk inwardly at 47 and 48 to form seats for the ball push-button 35 loosely held there-between.

The free end of the flexible spring strip 25 terminates in an outwardly bent hook 48a which 25 is adapted to obstruct the upper edge of the locking plate 43 and prevent upward longitudinal movement of the thumb-piece and ball until the hook 48 has been released therefrom by pressing the ball push-button 35 inwardly.

30

Operation

In operation, assuming the flashlight is in the open-circuit condition as shown in Fig. 1, if a temporary flash of the lamp is desired, it will 35 only be necessary to manually depress the ball 35 and hold it in as long as the light is wanted. In this position, it will be clear that the hook 48a on the spring strip 25 will lie below the plane of the locking plate 43 (see Fig. 3).

If a more permanent light is desired, the thumb-piece 40 may be slid upwardly by the operator to the position as shown in Fig. 4. In this position the ball 35 will lie in the "high" end section of the spring strip 25, thus automatically 40 holding said strip 25 in its innermost position. The lamp will then remain lighted until the switch is returned to "off" position by manually sliding the thumb-piece 40 downwardly.

Modified form

In the modified form of the invention shown 50 in Figs. 5, 6 and 7, the construction is similar to the first form shown in Figs. 1-4, except that a push-button member 49 in the form of a square cam is substituted for the ball 35, and a slideable thumb-piece 50 is provided, having a square hole 51 for accommodating said button 49. The inner portion of the push-button 49 is provided

with a convex lobe 52 which is adapted to fit into the offset section 53 of the spring strip 54. The function of the modified form of switch is similar in all respects to that of the first form shown in Figs. 1-4. Thus, the cam push-button 49 is normally forced outwardly by reason of the resiliency of the spring strip 54, and said button 49 is limited in its outward movement by means of a pair of opposed shoulders 55, 55 of said button formed at an intermediate position, and which are adapted to abut against the inner edges of a pair of inturned lugs 56, 56 formed at the opposite edges of the square hole 51 of the thumb-piece 50. The lugs 56, 56 also serve as a means for holding and guiding the push-button 49 when it is depressed. 15

It will be understood that when either form of flashlight is out of use, the danger of accidental sliding of the thumb-piece to prolonged closed-circuit position by contact with exterior articles, as when the flashlight is carried in a bag 20 or in the pocket, will be largely eliminated.

While there have been disclosed in this specification two forms in which the invention may be embodied, it is to be understood that these forms are shown for the purpose of illustration 25 only, and that the invention is not to be limited to the specific disclosures but may be modified and embodied in various other forms without departing from its spirit. In short, the invention includes all the modifications and embodiments 30 coming within the scope of the following claim.

Having thus fully described the invention, what is claimed as new, and for which it is desired to secure Letters Patent, is:

In a flashlight having a casing, an electric 35 lamp bulb, and a battery, switch mechanism for controlling the flow of current through said bulb including a stationary contact on said casing, a movable contact member for engaging said stationary contact and closing the circuit through 40 said bulb and battery, a thumb piece slidably mounted on the outside of said casing, a locking plate attached to said thumb piece and slideable within said casing, an upwardly extending spring strip secured at its bottom end to said casing and having a freely movable upper end in alinement with and insulated from said movable contact member, said strip having an outstanding hook on its free end for engaging the outer end of said locking plate to prevent accidental sliding of said thumb piece, and a depressible push-button carried by said thumb piece for moving said strip inwardly to light the bulb and to simultaneously release said hook from said locking plate to permit the thumb piece to be manually slid upwardly along said casing to permanent circuit-closed position.

JOSEPH F. MORAN.
